[57] **CLAIM**

The ornamental design for a wine bottle rack, as shown and described.

DESCRIPTION

FIG. 1 is a perspective view of a wine bottle rack in accordance with a first embodiment of the present invention, with wine bottles shown in phantom;

FIG. 2 is a front elevational view of the wine bottle rack shown in FIG. 1;

FIG. 3 is a rear elevational view of the wine bottle rack shown in FIG. 1;

FIG. 4 is a bottom plan view of the wine bottle rack shown in FIG. 1;

FIG. 5 is a top plan view of the wine bottle rack shown in FIG. 1;

FIG. 6 is a left side elevational view of the wine bottle rack shown in FIG. 1, with a wine bottle shown in phantom, the right side elevational view being a mirror image thereof;

FIG. 7 is a perspective view of the wine bottle rack shown in FIG. 1 attached to a shelf shown in phantom;

FIG. 8 is a front elevational view of a wine bottle rack in accordance with a second embodiment of the present invention;

FIG. 9 is a rear elevational view of the wine bottle rack shown in FIG. 8;

FIG. 10 is a bottom plan view of the wine bottle rack shown in FIG. 8;

FIG. 11 is a top plan view of the wine bottle rack shown in FIG. 8;

FIG. 12 is a left side elevational view of the wine bottle rack shown in FIG. 8, the right side elevational view being a mirror image thereof;

FIG. 13 is a front elevational view of a wine bottle rack in accordance with a third embodiment of the present invention;

FIG. 14 is a rear elevational view of the wine bottle rack shown in FIG. 13;

FIG. 15 is a bottom plan view of the wine bottle rack shown in FIG. 13;

FIG. 16 is a top plan view of the wine bottle rack shown in FIG. 13; and,

FIG. 17 is a left side elevational view of the wine bottle rack shown in FIG. 13, the right side elevational view being a mirror image thereof.

The broken lines are for illustrative purposes only and form no part of the claimed design.
